D19121

UNITED STATES PATENT OFFICE.

JOHN F. SIMONS, OF PHILADELPHIA, PENNSYLVANIA.

DESIGN FOR A THIMBLE.

SPECIFICATION forming part of Design No. 19,121, dated May 28, 1889.

Application filed February 15, 1889. Serial No. 300,060. Term of patent 14 years.

To all whom it may concern:

Be it known that I, JOHN F. SIMONS, a citizen of the United States, and a resident of Philadelphia, Pennsylvania, have invented a new and original Design for a Thimble, of which the following is a specification.

My design for the ornamentation of a thimble is fully illustrated in the accompanying drawings, in which—

Figure 1 is a side view, and Fig. 2 is a section on the line 1 2, Fig. 1.

The leading feature of the design is the vertically-ribbed base portion of the thimble.

A is the ordinary top of the thimble; B, the base. The base has a series of vertical ribs, *a* and *b*. The ribs *a* are made with plain surfaces. The ribs *b* are narrow, slightly round-

ed, and also plain, and situated between the ribs *a*. On each side of the ribs *a* are ribs *c c*. These ribs are ornamented, as fully shown in the drawings.

I claim—

The design for a thimble, said design consisting of a series of vertical plain ribs, *a* and *b*, with ornamented ribs *c c*, substantially as described and shown.

In testimony whereof I have signed my name to this specification in the presence of two subscribing witnesses.

JOHN F. SIMONS.

Witnesses:

WILLIAM D. CONNER,
HARRY SMITH.
